UNITED STATES PATENT OFFICE.

HIRAM MENDENHALL AND ALBERT T. KILLINGER, OF AUDUBON, IOWA.

IRONING-BOARD.

1,235,147.

Specification of Letters Patent.

Patented July 31, 1917.

Application filed January 5, 1916. Serial No. 70,535.

To all whom it may concern:

Be it known that we, HIRAM MENDENHALL and ALBERT T. KILLINGER, of the United States, residing at Audubon, in the county 5 of Audubon and State of Iowa, have invented new and useful Improvements in Ironing-Boards, of which the following is the specification.

This invention relates to improvements in 10 ironing boards and particularly to an instantly detachable ironing board of simple, economical and improved form.

It is an object of the invention to provide an ironing board which when not in use can be folded up flat to take up very little room, but when in use may be applied instantly to 15 a wall by means of one or two small and inconspicuous hooks, fastened in the wall and which is instantly detachable from the wall.

20 It is another object of this invention to provide an ironing board having an extensible tongue for ironing sleeves or the like, the upper surface of which tongue is flush with the ironing board.

25 It is another object of the invention to provide an ironing board having provision for the instant detachment and release of a cover cloth of the ironing board.

30 It is a further object of the invention to provide an ironing board having in combination adjustable means by which the board may be attached to the wall and a raised platform for the reception of a hot iron.

Other objects and advantages of the 35 invention will appear as the description to follow proceeds.

In the drawings:

Figure 1 is a plan view, partly in section of our new ironing board.

40 Fig. 2 is a bottom view thereof.

Fig. 3 is a cross sectional view showing the board attached to the wall.

Fig. 4 is a cross sectional view on a line 4-4 of Fig. 1.

45 Fig. 5 is a cross sectional view showing in detail the method of attachment.

Fig. 6 is a plan view of the modification of attaching means.

Fig. 7 is a detailed view in cross section 50 of a modified attaching means.

Fig. 8 is a plan view of a modification of the attaching means.

An ironing board constructed according to our invention is preferably made of 55 matched strips 1, tongue and grooved as in-

dicated in Fig. 4, and having a perfectly smooth upper surface. The bottom of the ironing board is provided with cross pieces 2 which serve to additionally bind the matched strips together, certain of these cross pieces 2 being centrally cut away as indicated at 3 for the reception of the folding bracket hereinafter referred to. The ironing board tapers at one end as indicated at 4 and is provided centrally with an extensible tongue 5 slidably mounted by a tongue-and-groove arrangement in the matched strips 4 so that the tongue 5 can be extended if desired, for ironing sleeves or the like. It is an important feature of the 60 invention that the upper surface of the tongue 5 is flush with the upper surface of the board so that the adjacent portion of the board and the tongue 5 when extended may be used as a continuous surface when ironing. To cover up the recess in the board made when the tongue 5 is extended, we provide a thin metallic plate 6 as indicated in Fig. 1, preferably slightly inset into the face of the board so as to make the surface of the 65 board smooth. In the actual construction of the ironing board the entire surface of the board is covered with a layer of asbestos padding not shown, and a separate layer of asbestos padding is glued or otherwise fastened upon the tongue 5.

The board is provided upon its under surface with side flanges 7, secured to the ends of the cross pieces 2 except the first thereof, which is extended to the edges of 70 the board. In the inner sides of these flanges 7, we provide pins 8 upon which a covering cloth for the board may be instantly hooked and tightly stretched across the board, and from which it may be instantly released. Mounted upon the rear end of the board is a cross piece 9 firmly secured to the board, upon which are mounted one or more plates 10 and provided with aperture 11, a portion of the plate 10, the 75 under and adjacent aperture being cut out as indicated at 12. Suitably spaced and firmly screwed into the scantling 13 in the wall or other firm vertical support, and projecting slightly beyond the plaster layer 14 80 are hooks 15. (See Fig. 5). Mounted upon the bottom of the board is a foldable brace 16, which by itself does not constitute a novel feature having been fully described 85 in our prior Patent No. 1,034,021. Suffice 90

to say however, this brace may be extended as shown in Fig. 3 and will collapsibly fold up against the bottom of the board and into the recess of the cross pieces 2 as shown 5 in Fig. 2.

In attaching the board to a wall, the brace 16 is first extended, the board is then tilted upwardly and so manipulated that the hooks 15 pass through the cutaway portion 12 and 10 aperture 11, whereupon the board is allowed to come to a horizontal position and a firm bearing is obtained against the wall through all the region between the point of contact of the hooks 15 and the plates 10 15 and the bottom of the brace 16. Weight or downward pressure upon the board simply serves to increase the frictional engagement of the rear end of the board and the back member of brace 16 with the wall and prevents tilting. For this reason a modification 20 is shown in Fig. 6 in which only one screw 11 and one hook 15' may be employed. The friction between the rear of the board and the rear member of the brace 16 against 25 the wall serves to prevent the board from tilting sidewise.

In Fig. 6 is shown a modification employing a solid board of the form shown and without an extensible tongue.

30 In Fig. 7 is shown a modification of securing means in which a screw eye 18 is secured in the wall by means of a long shank 19 which screws into a scantling or the like, and a hook 19' having a turned down forward end 20 and a screw shank 21 secured into the board through the platform 9, is employed, the board being cutaway at its rear end to accommodate the screw eye as shown at 22. This modification of the invention 35 has certain advantages over the other form shown in that the connecting members between the board and the wall may be adjusted with a greater degree of precision because only a half turn of the screw eye is necessary to bring it from one 40 operable position to another operable posi-

tion, at the same time moving it in or out of the wall, whereas a full turn of the hook 15 is necessary to produce the same result.

In Fig. 8 another modification is shown 50 which consists in using a plate 10' on one side of the platform 9 having a slot 10" therein making the attachment more easy than if two apertures 11 were used.

We claim—

55 1. In an apparatus of the class described, an ironing board, an extensible tongue mounted therein with its upper face flush with the face of the ironing board, and a cover plate to cover the aperture produced by the extension of said tongue.

2. In an ironing board, a platform adjacent the rear end of the board and firmly mounted thereon, a pair of plates having apertures therein and mounted at the rear 65 corners of said board, hooks having shanks adapted to extend into the support and upturned front ends adapted to take into said apertures, the board under said plates and adjacent said apertures being cut away to 70 permit the rear end of the board to fit snugly against the support when the board is attached thereto.

3. In an ironing board, a hook and an apertured member to receive the same, one 75 of said members being adapted to extend into a support and to be rigidly anchored therein, a cross piece mounted at one end of the ironing board and supporting the apertured member whereby the board may be 80 readily mounted upon or removed from the support and the bearing surface of the butt end of the board is substantially increased.

In witness whereof, we hereunto subscribe our names to this specification in the 85 presence of two witnesses.

HIRAM MENDENHALL,
ALBERT T. KILLINGER.
